UNITED STATES PATENT OFFICE.

JOHN S. MACLEAN, OF COLUMBUS, OHIO.

DRAWER.

No. 838,037.

Specification of Letters Patent.

Patented Dec. 11, 1906.

Application filed December 16, 1905. Serial No 291,987.

To all whom it may concern:

Be it known that I, JOHN S. MACLEAN, a citizen of the United States, residing at Columbus, in the county of Franklin and State 5 of Ohio, have invented certain new and useful Improvements in Drawers; and I do hereby declare the following to be a full, clear, and exact description of the invention, such as will enable others skilled in the art to 10 which it appertains to make and use the same.

The object of the invention is to provide a drawer and frame for cases, furniture, and the like with means whereby the weight of 15 the drawer is entirely supported on rolling bearings and with means for keeping the sides of the drawer from contact with the sides of the frame. Incidentally I provide means to prevent the drawer from tilting 20 down at the front when it is pulled out into open position, and also to prevent the drawer from being accidentally pulled entirely out.

The invention consists in the construction hereinafter described and claimed.

25 In the accompanying drawings, showing but one embodiment of the invention, Figure 1 is a vertical sectional view taken on the plane $x x$, Fig. 2, looking to the left. Fig. 2 is a vertical sectional view taken on the plane 30 $y y$, Fig. 1, looking to the right. Fig. 3 is a detail illustrating the device for antifrictionally supporting the inner end of the drawer. Fig. 4 is a sectional view of a common form 35 of ball-bearing for supporting the sides of the drawer at the front end of the frame.

In the views, 1 designates the drawer, the outer end of which is at the left-hand side of Fig. 1. Secured along the middle of the under side of the drawer is a grooved strip 1^a , 40 and along the under side near the edges of the drawer are metallic strips 1^b . The frame in which the drawer slides is designated 2, and along the middle of the bottom of this is a tongued piece or bead 2^a , that projects into 45 the grooved strip 1^a , and at the front corners of the bottom of the frame 2 are ball-bearings 2^b , upon which the metallic side strips 1^b run.

50 Secured to the inner side of the inner vertical wall of the drawer is a metallic bar 3, footed with a small roller 3^a . The bar 3 is slidably secured in metallic clips 3^b , and the latter are provided with set-screws 3^c to pinch the bar and hold it in the position to 55 which it is adjusted. The roller 3^a rests and runs on top the tongued bead 2^a .

In practice the bar 3 is so adjusted that the roller 3^a supports the weight of the inner end of the drawer and not the tongued bead 2^a , thereby relieving the friction that would 60 be engendered by close contact between the horizontal surfaces of the tongued bead and the grooved strip 1^a . The chief if not the sole function of the tongued bead and the grooved strip is to prevent horizontal move- 65 ment of the drawer toward the sides of the frame, as this is the most potent cause of trouble in working a drawer. The ball- 70 bearings 2^b are also of such height that when fastened into place they coöperate with the roller 3^a in holding the drawer up, so that the horizontal surface of the tongued bead 2^a and the grooved strip 1^a shall not contact. It will be thus observed that while the 75 tongued bead 2^a and grooved strip 1^a effec- 75 tually prevent sidewise movement of the drawer the weight of the latter is supported on rolling bearings. This construction eliminates entirely the trouble incident to sticking at the side and at the same time makes the 80 drawer easy to move.

To prevent the outer end or front of the drawer from tilting down when it is drawn out to an extent where its center of gravity is beyond the supports, I provide the upper 85 end of the bar 3 with a small roller 3^d , journaled in a bracket that slides on the bar 3, said bracket being provided with a set-screw 3^e to secure it in the position to which it is adjusted. Along the middle of the top of 90 the frame 1 (and constituting a part of the frame when the roller 3^d is used) is a bar 2^c , against which said roller 3^d bears as the drawer is moved in and out. This contact of the roller 3^d with the bar 2^c sustains the 95 drawer in horizontal position when the latter is drawn out without very greatly increasing the friction between the drawer and frame. To prevent the drawer from being accidentally entirely pulled out, the frame at the outer 100 end of the bar 2^c is furnished with a downwardly-projecting stop 2^d , against which the roller 3^d impinges when the drawer is drawn nearly completely out.

What I claim, and desire to secure by Letters Patent, is—

1. In furniture, cases and the like, the combination with a drawer-frame provided with antifriction drawer-supporting devices at its outer end and a tongue-strip extending 110 in the direction of movement of the drawer, of a drawer to slide in said frame provided

with an antifriction device at its inner end adapted to ride upon said tongue-strip to support the weight of the drawer at that end and a groove-strip on the drawer adapted to engage said tongue-strip to prevent horizontal sidewise movement of the drawer.

2. In furniture, cases and the like, the combination with a drawer-frame provided with antifriction drawer-supporting devices
  - 10 at either side of its outer end, of a drawer to slide in said frame provided with a single antifriction device at the lower side of its inner end to support the weight of the drawer at that end, and a guiding device between the drawer and frame to prevent horizontal sidewise movement of the drawer, one member of said guiding device affording a track for the antifriction device at the inner end of the drawer.
  - 15 3. In furniture, cases and the like, the combination with a drawer-frame provided

with antifriction drawer-supporting devices at either side of its outer end, of a drawer to slide in said frame provided with a single antifriction device at the lower side of its inner end to support the weight of the drawer at that end, an antifriction device at the upper side of its inner end to contact with the frame to prevent the downward tilting of the outer end of the drawer when opened,²⁵ and a guiding device between the drawer and frame to prevent horizontal sidewise movement of the drawer, one member of said guiding device affording a track for the antifriction device below the inner end of the drawer.³⁰

In testimony whereof I affix my signature in presence of two witnesses.

JOHN S. MACLEAN.
